O. L. GAMMELL

CUFF BUTTON

Filed Sept. 19, 1923

Inventor
Ove L. Gammell

By Horatio E. Bellows

Attorney

UNITED STATES PATENT OFFICE.

OVE L. GAMMELL, OF ATTLEBORO, MASSACHUSETTS, ASSIGNOR TO SMITH AND CROSBY,
OF ATTLEBORO, MASSACHUSETTS, A FIRM COMPOSED OF ALFRED D. CROSBY AND
GEORGE H. CROSBY.

CUFF BUTTON.

Application filed September 19, 1923. Serial No. 663,611.

To all whom it may concern:

Be it known that I, OVE L. GAMMELL, a citizen of the United States, residing at Attleboro, in the county of Bristol and State 5 of Massachusetts, have invented certain new and useful Improvements in Cuff Buttons, of which the following is a specification.

My invention relates to separable buttons comprising two interengageable button units 10 particularly adapted for use in cuffs and analogous articles of wearing apparel.

The essential objects of my invention are security against accidental detachment of the units one from the other; adaptability 15 for facile manipulation in locking and unlocking; certainty and power of interlocking action; to prolong the life of the resilient locking elements and protect the same from distortion or bending; and to attain these 20 ends in an inexpensive structure and one in which the parts are not subject to excessive wear.

To the above ends essentially my invention consists in such parts and in such combinations of parts as fall within the scope 25 of the appended claims.

In the accompanying drawings which form a part of this specification,

Figure 1 is a side elevation, partially in 30 central vertical section, of a button embodying my invention showing the parts locked or fully engaged,

Figure 2, a section of the same taken on line 2—2 of Figure 1, showing the parts unlocked and in position of nearly complete 35 disengagement,

Figures 3, 4, and 5, sections on lines 3—3, 4—4, and 5—5 respectively of Figure 1, and

Figure 6, a detail perspective view of the 40 disassembled shell and its contained operative parts arranged in assembled sequence.

Like reference characters indicate like parts throughout the views.

My button comprises a socket member 10 and an entering member 11. The latter comprises a head 12, shank or post 13, and base or flange 14, centrally of which is a stud comprising a neck 16 and a hemispherical overhanging head 17 having a flat horizontal 50 under surface.

The socket member comprises a head 19, a doubly tapering hollow shank or post 20 whose inner extremity forms a flange portion 21 embraced by a bead or flange 22 55 formed on the side 23 of a casing or shell

24 having a closed inner end 25 provided with a circular central opening 26 surrounded by an internal hub or shoulder 27. The side 23 is provided with an oblong peripheral slot 29, having an extension 60 cavity 30 forming a shoulder 31. Rotatably mounted on the hub 27 through a central opening 33 is an operating disk 34 provided at opposite sides of the opening with axial lugs 35. Upon the periphery of the disk is 65 a neck or arm portion 36 of a finger piece 37. The portion 36 is slidable in the slot 29. Abutting against the disk, and oppositely disposed relatively to each other upon opposite sides of the center of the disk, are 70 two flat resilient cam members 38. In detail each cam member comprises an arcuate arm 39 abutting against the side 23 of the casing, terminating at one end with a loop 40 formed by an integral curved finger 41 75 terminating in a cam 42 having a straight cam edge 43 engaging near its outer end one of the lugs 35. It will be understood that the loop 40 and finger 41 are resilient, and that the cam edge 43 in its normal or contracted position partially or segmentally 80 closes the opening 26 of the shell. Each arm 39 is maintained against displacement by cavities 45 into which extend peripheral lugs or projections 46 on a retaining 85 plate 47 adjacent the flange portion 21 of the post 20, and is provided with a central opening 48. In this instance the plate 47 is secured by peripheral lug 49 fitted in slot portions 30 and 31 of the casing against the 90 shoulder 31.

The button holes of the cuffs surround the shanks 13 and 20 of the button members. To interengage the members the head 17 of the stud is pushed through the opening 26, and its rounded or pointed end, entering between the cams 42 and contacting with their edges 43 in its path, distends the cams in its passage, as shown in Figures 2 and 4. As soon as the head in its advance has passed beyond the cams, the latter are forced inwardly by the resilient fingers 41 and loops 40 against the stud neck 16 below or behind the head 17, as shown in Figures 1 and 3, and prevents any accidental disengagement of 100 the button members. To unlock and separate these members the finger piece 37 is manually pushed in the direction of the arrow shown in Figure 4 whereby the lugs 35 are caused to move along the cam edges 105 110

43 thereby distending the cams 42 to points outside the path of the head whereupon the latter may be withdrawn.

Having thus described one illustrative embodiment of my invention, it is understood that the specific terms employed are used in a descriptive sense only, and are not for the purpose of limitation, the scope of the invention being defined by the appended 10 claims.

I claim:-

1. A separable cuff button formed in two parts each having a post, a stud carried by one post, a casing supported by the other post provided with an opening to receive the stud, yieldable cam members mounted within the casing extending across the opening adapted to engage and retain the stud, and rotatable means in the casing engaging the cams for releasing the stud. 15

2. A separable cuff button formed in two parts each having a post, a stud carried by one post, a casing carried by the other post provided with an opening to receive a stud, 25 oppositely disposed vibratory cam members mounted in the casing across opposite portions of the opening into and out of the path of the stud, and manually operable rotatable means in the casing for actuating the cam members. 30

3. A separable cuff button formed in two parts each having a post, a stud carried by one post, a casing carried by the other post provided with an opening to receive the stud, oppositely disposed resilient cam members spaced apart and supported in the casing normally closing opposite portions of the opening, an operating disk rotatably mounted in the casing, and provided with 35 an opening registering with the first opening, and lugs on the disk extending between the cam members and engageable therewith. 40

4. A separable cuff button formed in two parts each having a post, a stud carried by one post, a casing carried by the other post provided with an opening to receive the stud and with a lateral slot, a retaining plate 45

in the casing, an operating disk rotatably mounted in the casing and provided with a central opening adapted to register with the first opening, axial lugs on the disk, a finger piece on the disk extending through the slot, and oppositely disposed resilient members comprising arms fast at one end to the retaining plate, loops on the opposite ends of the arms, resilient fingers on the loops, and cams on the fingers spaced from each other across the openings and engageable by the lugs. 50

5. A separable cuff button formed in two parts each having a post, a stud supported by one post, a stud carried by the other post provided with an opening to receive the stud and with a lateral slot, a retaining plate 55 fast in the casing provided with a central hole in alignment with the first opening and with marginal projections, an operating disk rotatably mounted in the casing and provided with a central opening registering with the first opening, lugs on the disk, a finger piece on the disk extending through the slot, and oppositely disposed cam members comprising arms provided with cavities for receiving the projections, resilient 60 fingers on the arms, and cams on the fingers engaged by the lugs and disposed transversely of the openings and hole. 65

6. A separable cuff button formed in two parts each having a post, a stud carried by one post comprising a neck and a hemispherical head provided with a flat bottom surface, a casing supported by the opposite post provided with an opening to receive the head and neck, and yielding members 70 mounted within the casing extending across the opening adapted to be displaced by the head and engage the neck, and a rotatable member cooperating with said members to 75 distend the latter outward. 80

In testimony whereof I have affixed my signature.

OVE L. GAMMELL
